UNITED STATES PATENT OFFICE.

EARL M. ZEEK, OF MARION, INDIANA.

PENHOLDER.

SPECIFICATION forming part of Letters Patent No. 709,130, dated September 16, 1902.

Application filed January 29, 1902. Serial No. 91,798. (No model.)

To all whom it may concern:

Be it known that I, EARL M. ZEEK, a citizen of the United States, residing at Marion, in the county of Grant, State of Indiana, have 5 invented certain new and useful Improvements in Penholders; and I do hereby declare the following to be a full, clear, and exact description of the invention, such as will enable others skilled in the art to which it appertains to make and use the same.

This invention relates to penholders; and it has for its object to provide a construction consisting of but three parts, so constructed and arranged as to reduce the cost of manufacture to a minimum, and which may be operated to discharge a pen therefrom without requiring the pen to be grasped.

A further object of the invention is to provide a construction wherein the pen will not be 20 liable to accidental discharge from the holder.

In the drawings forming a portion of this specification, and in which like numerals of reference indicate similar parts in the several views, Figure 1 is a side elevation showing 25 the complete penholder with a pen in place therein. Fig. 2 is a central longitudinal view of the handle portion of the penholder. Fig. 3 is a side elevation of a modified form. Fig. 4 is an end view of a modification.

Referring now to the drawings, the present 30 penholder consists of the handle portion, including the front cylindrical part 5 and the rear tapered part 6. In the part 5 of the handle is formed a recess 7, extending longitudinally thereof and passing through the front end of the handle, and in the bottom of the recess is formed a slot 8, which extends entirely through the handle from one face to the other, the rear end of the slot having a 35 laterally-offset portion 9.

Slidably disposed upon the portion 5 of the handle of the holder is a sleeve 9', of suitable metal and which fits said portion snugly, the depth of the recess 7 being such that a pen may 40 be crowded with its rear end into the recess, so that its edges will rest against the bottom of the recess and the uppermost portion of its

curvature will contact with the inner surface of the sleeve. The pen will be thus held securely from dropping from the holder. 50

Through the slot 8 is passed a pin 10, the ends of which are engaged with perforations 11 in the sleeve and are upset or riveted to prevent withdrawal.

In the operation of this penholder the 55 sleeve is moved rearwardly until the pin engages the rear end of the slot 8, after which the sleeve is rotated to engage the pin with the laterally-offset portion of the slot to prevent forward movement of the sleeve. The 60 pen is passed with its rear end into the recess until it engages the pin, when it is in position for use. In this position of the pen the tapered rear end of the stem of the pen projects with its central portion slightly beyond 65 the front face of the pin, and thus the pin is prevented from accidental lateral movement and is held weakly from entering the main or longitudinally-extending portion of the slot. When the pen is to be discharged, 70 the sleeve is rotated forcibly upon the handle until the pin is brought into the longitudinal portion of the slot, and the sleeve is then moved longitudinally of the handle, so that the pin is pressed against the rear end of the 75 stem of the pen and the latter is forced from the holder.

If desired, the material of the handle may be slotted at the sides of the recess, as shown in Fig. 3, so that a yieldable tongue is formed, 80 so that pens of various thicknesses may be engaged with the holder, it being understood, as shown, that the portion 5 of the handle is hollow.

In practice other modifications of the invention may be made and any suitable materials and proportions may be used without departing from the spirit of the invention. 85

What is claimed is—

A penholder comprising a handle having 90 one end hollow, the hollow end portion of the handle having a longitudinally-extending recess opening through the end of the holder, and having a slot formed through the bottom

of the recess and having its rear end directed laterally, a sleeve slidably and rotatably mounted upon the hollow end portion of the handle and covering the recess, a pin engaged with the sleeve and passed through the slot and movable therethrough as the sleeve is moved longitudinally and rotated, said sleeve having also longitudinal cuts formed through the bottom of the recess in the planes

of the side walls of the latter and entering the 10 hollow of the handle.

In testimony whereof I affix my signature in presence of two witnesses.

EARL M. ZEEK.
